LOUDSPEAKER ENCLOSURE

Naoki Tominaga, Osaka, Japan, assignor to Sanyo
Electric Co., Ltd., Osaka, Japan

Filed Feb. 5, 1969, Ser. No. 15,631

Claims priority, application Japan Aug. 23, 1968

Term of patent 7 years

Int. Cl. D14—01

U.S. Cl. D26—14

FIG. 1 is a perspective view of the loudspeaker enclosure of the present invention;

FIG. 2 is a front elevational view of the loudspeaker enclosure shown in FIG. 1;

FIG. 3 is a rear elevational view of the loudspeaker enclosure shown in FIG. 1; and

FIG. 4 is a side elevational view of the loudspeaker enclosure shown in FIG. 1 and is identical to the top plan, bottom plan and side view opposite to that shown in FIG. 4.

I claim:

The ornamental design for a loudspeaker enclosure, as shown and described.
